UNITED STATES PATENT OFFICE.

GEORGE H. CHAPPELL, OF NEW YORK, N. Y.

MOTOR.

SPECIFICATION forming part of Letters Patent No. 440,913, dated November 18, 1890.

Application filed August 7, 1890. Serial No. 361,352. (No model.)

To all whom it may concern:

Be it known that I, GEORGE H. CHAPPELL, a citizen of the United States, and a resident of New York, in the county of New York and 5 State of New York, have invented certain new and useful Improvements in Motors, of which the following is a specification.

Figure 1 is a side view of my improved spring-motor. Fig. 2 is an end view of the 10 same. Fig. 3 is an enlarged side view of the tripping device; Fig. 4, a top view of the same; and Fig. 5, a cross-section of the mechanism through line α of Fig. 1, with portion of the 15 disk cut away, showing the arrangement of the mechanism.

The object of my invention is to provide a spring-motor so constructed and arranged that while in the process of winding up the 20 spring or springs the same amount of force will be exerted on the driven mechanism. It also provides a series of spring-motors arranged on the same shaft, whereby the first 25 of the series can be employed to drive the mechanism and at the proper time the second of the series will be thrown into the gear and the first released, and so on. Inversely, 30 in the process of winding, the same crank or other means for winding can be used to wind up the entire series, winding up each in succession, and each being so arranged that when 35 one is wound the one next following will be wound up, and so on. It is found to be impracticable to employ the tension of a single spring to operate mechanism for any great 40 period of time. Several springs in a train or series will produce better results, provided they are so arranged as to work successively by the action of the mechanism itself; and it is essential that such a train of mechanism to 45 be a practical and commercial success should be made as simple and cheap as possible. My mechanism for this purpose provides a single shaft or arbor on which I place the entire series of springs and gearing, each of which, 50 while entirely independent of the others in its action, is nevertheless dependent on the one next to it, so far as the time of its action is concerned.

Referring now to the accompanying drawings, the frame of the mechanism is shown as 55 composed of the two end standards A A, pro-

vided with a horizontal beam B near the base and a bar C at the upper end.

D represents the arbor or shaft for the 55 spring journaled in the standards midway, and E is a line-shaft to which power is imparted from the spring mechanism. One end of the arbor D has a crank F for winding the 60 springs; but instead of the crank other means may be employed for that purpose.

The arbor D is designed to carry a series of 65 springs and gear-wheels, and as they are duplicates of each other a description of one will be sufficient for all. In Fig. 1 I show one of the series with the main gear-wheel in section and having a spring attached, while in the other the main gear-wheel is shown without an accompanying spring. This main gear-wheel G has external teeth H, which mesh with the teeth of the gear I on the line-shaft 70 E. The wheel G has also ratchet-teeth J externally and internally the teeth K. The gear G is placed loosely on the shaft D, and on that side of the gear having the internal teeth K a barrel L is placed loosely on the 75 shaft. This barrel has a disk M facing the gear G. Between the gear G and the disk M a pinion N is secured to the shaft D by means of the key O, or otherwise, and intermediate between the pinion N and internal gear K is a small pinion P. I prefer to have 80 one of these pinions P on each side of the central pinion, as shown in Fig. 5, and these small pinions are journaled to the pins Q, which project from the inner face of the disk M. It 85 will thus be seen that while the central pinion N turns with the shaft D the barrel L and gear G are loose on the shaft and operated only through the medium of the pinions N P. On the inner face of the disk M near the 90 teeth J is a pawl R, hinged thereto, which engages with the ratchet-teeth J. A spring S, attached to the barrel L and wound around the same, has its opposite end attached to the 95 bar C of the frame.

The gear I on the line-shaft E is placed loosely thereon, and the hub thereof is provided on one side with a toothed clutch T, while on the opposite side of the gear is a spring U around the shaft, which acts between 100 the gear and a suitable collar on the shaft so as to keep the gear in engagement with the

toothed clutch when turned in one direction, but at the same time will permit the gear to reverse or turn in the opposite direction independently of the shaft E. Any form of clutch 5 may be used for this purpose; but I have merely indicated this form in order to show the manner of operating the device when a series of springs and gears are employed.

A train of the gears, disks, and springs is 10 placed on the arbor; but I have herein shown only two sets of gears and disks, the spring being removed from the second set.

In order to be able to throw the successive 15 springs and gears into action, I have devised an automatic tripping device, which consists of the wheel V, having, as shown in Fig. 4, the eight points or spurs W. This is journaled to the beam B of the frame. Attached 20 to its spindle and beneath the wheel V is a small pinion X. A bar Y, having one of its ends bent upwardly, so as to engage with the teeth H of the gear G, is provided on one side with suitable teeth to engage with the pinion X and is confined in suitable housings or 25 guides, so as to permit the bar to run back and forth as the wheel V is turned. A spur or pin Z, attached to the periphery of the disk M, engages with the teeth W of the wheel V, and causes the latter to rotate the distance of 30 one tooth at each rotation of the disk M.

The operation of the invention is as follows: We will suppose that the spring S is 35 completely unwound and it is desired to wind up the mechanism. The crank F is brought into requisition, turning the shaft D to the left, thus moving the pinion N in the direction shown by the arrow. The effect of this is to turn the pinions P to the right, as shown, and since the latter are attached to the bar 40 rel-disk M the latter turns to the left, thus winding up the spring S. At the same time, the gear G being in engagement with the gear I, there is no change in motion imparted to the gear G, since the action of winding by 45 the crank releases the pawl R, which travels back over the ratchet-teeth J and engages again the moment the crank is released. When the force of the first spring is exhausted, the wheel V having meanwhile been 50 rotated by the action of the spur Z, the bar Y becomes disengaged from the teeth of the wheel G in the next series, causing the spring in that system to operate. The force is then imparted by the second gear G on the arbor 55 D to the second gear I on the line-shaft E, so that while the first gear is still in engagement with the gear G and the latter is still in motion it is necessary to prevent the gear I from turning or acting on the first spring.

60 This is accomplished by attaching the clutch T, as shown. It is obvious that this same system may be employed with equal facility with weights instead of springs, and for some purposes weights are preferable.

65 One of the important features of this invention is its adaptability to use one or more

springs at the same time. If it is constructed with a large number of springs in the train, an immense power can be exerted by throwing on the entire series, or only one or two 70 can be used; or, instead of throwing on each spring in succession, the same mechanism can be adapted to throw on two sets of springs at the same time, or more, all of which can be accomplished without departing 75 from the spirit of my invention.

What I claim as new is—

1. A motor composed of an arbor having thereon a loose gear with internal and external teeth, and by the side of said gear a loose 80 barrel having a disk and a spring on said barrel, and between said disk and gear a pinion secured to the arbor, and intermediate pinions journaled to the face of the disk, which intermediate pinions engage with the 85 tight pinion on the arbor and the internal teeth of the large gear, substantially as herein set forth.

2. The herein-described mechanism for winding motors and imparting motion to a 90 line-shaft, which consists of an arbor having thereon in series a loose wheel having external gear and ratchet teeth and internal gear-teeth, a toothed gear fixed to the shaft, intermediate gear-wheels secured to a disk between the fixed gear and the internal gear-wheel, a loose disk on the shaft having a barrel integral therewith and a spring thereon, and a pawl secured to the disk and engaging with the ratchet-teeth, substantially as herein 95 set forth.

3. A motor composed of a single arbor, in combination with a loose wheel having external gear and ratchet teeth and intermediate gear-teeth, a barrel loosely placed on the arbor 105 having a disk on one end provided with a pawl and two pinions, a tight pinion on the arbor engaging with the small pinions on the disk, and a spring for operating the same, substantially as herein set forth.

4. In a motor, the single arbor carrying a loose wheel having external gear and ratchet teeth and internal gear-teeth, and a loose barrel having a disk at one end, said arbor having between the gear and disk a fixed pinion and between said pinion and the internal teeth of the gear and engaging therewith a small pinion journaled to a stud on the disk, in combination with a pawl on the inner face of the disk and adapted to engage the aforesaid ratchet-teeth, the spring on the arbor-barrel, and a clutch-gear on the line-shaft, substantially as herein set forth.

5. In a motor, the single arbor carrying a loose wheel having external gear and ratchet 120 teeth and internal gear-teeth, and a loose barrel having a disk at one end, said arbor having between the gear and disk a fixed pinion and between said pinion and the internal teeth of the gear and engaging therewith a small pinion journaled on a stud on the disk, 125 in combination with a pawl on the inner face

of the disk and a stud on its outer face, and the tripping mechanism, consisting of a toothed wheel having a small pinion and a toothed bar engaging with said pinion, one end of which engages with the teeth of the next gear-wheel, substantially as herein set forth.

Signed at New York, in the county of New York and State of New York, this 4th day of August, A. D. 1890.

GEORGE H. CHAPPELL.
